Primary Examiner — Jae Liang*Assistant Examiner* — Tia Ruth-Renee Polidori(74) *Attorney, Agent, or Firm* — Cantor Colburn LLP(57) **CLAIM**

The ornamental design for a refrigerator, as shown and described.

DESCRIPTION

FIG. 1 is a perspective view of a refrigerator, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is rear perspective view thereof.

The broken lines illustrating portions of the refrigerator form no part of the claimed design.

The dot-dash broken lines represent a border between claimed and unclaimed subject matter and form no part of the claimed design.

1 Claim, 8 Drawing Sheets(58) **Field of Classification Search**

CPC 2321/147; F25D 2323/02; F25D 2323/023;
F25D 2400/12

See application file for complete search history.
